To all whom it may concern:

Be it known that I, GUSTAV GASTRICH, a citizen of the United States of America, residing at Wyomissing, in the county of Berks and State of Pennsylvania, have invented a new, original, and ornamental Design for a Stocking, of which the following is a specification, reference being had to the accompanying drawing, forming part thereof.

Fig. 1 is a side elevation of a stocking embodying my design, and shows the latter approximately to normal scale.

Fig. 2 is a plan view, on an enlarged scale, of a section of the fabric.

Fig. 3 is a plan view of a section of the fabric shown enlarged approximately $1\frac{1}{2}$ times actual size, but which in the reduction to patent size will show the fabric approximately actual size.

I claim:

The ornamental design for a stocking as shown and described.

In testimony whereof I affix my signature.

GUSTAV GASTRICH,
